UNITED STATES PATENT OFFICE.

CECIL H. BOYULS, OF LOUISVILLE, KENTUCKY.

COLLAR-BAND HOLDER.

Application filed December 1, 1921. Serial No. 519,124.

To all whom it may concern:

Be it known that CECIL H. BOYULS, citizen of the United States of America, residing at Louisville, in the county of Jefferson and 5 State of Kentucky, has invented certain new and useful Improvements in Collar - Band Holders, of which the following is a specification.

This invention relates to ironing machines 10 and has special reference to a collar band holder for ironing machines of the type used for ironing shirts and other similar garments.

Heretofore it has been customary in iron- 15 ing machines to provide collar band holders but these holders, wherever adjustability was provided for different sized collar bands, have usually sought to accomplish the holding of the collar band by stretching 20 the same around an expandible form.

This method of securing a collar band in position over an ironing machine has been found to be very objectionable by reason of the fact that this stretching process made it 25 necessary to button the ends of the collar band together so that when the band was stretched a very considerable degree of tension was brought on the collar band holders with considerable tearing out and injury to 30 the garment.

One important object of the present invention is to provide an improved construction 35 of collar band holder wherein the collar band will be securely held in proper ironing position without any stretching whatever.

In certain of the former types of collar band holder employing an expandible member and requiring the buttoning of the band a certain amount of the shirt front, in open 40 front shirts, necessarily overlapped and thus there was great difficulty in properly ironing this overlapping portion. In some instances the extent of overlapping has been reduced by separating the lower part of the shirt 45 front while in other instances a pressing member has been interposed between the overlapping portions. Both of these methods have been found clumsy and ineffective.

A second important object of the invention 50 is to provide a collar band holder which will securely hold the collar band in proper position with the ends of the band more or less separated as the operator desires, thus leaving the entire front of an open front shirt in such position that it may be readily

acted upon by the swinging iron used in ironing machines, none of the parts overlapping.

In machines for ironing shirts there is usually provided a fixed platen for a movable iron mounted to come into pressing contact with a shirt held on the platen, the iron usually covering the bosom. In such machines the iron is provided with a recess to receive the collar band holder which is mounted on the platen. 60

A third important object of the invention is to provide an improved, easy and definite means of adjusting the collar band holder to proper alinement with the moving iron so that the holder may fit closely within the 70 recess provided and thus enable the iron to press close up to and all around the collar band at its junction with the bosom of the shirt. 65

Ironing devices for this purpose are usu- 75 ally provided with a padded surface just as is common with the ordinary domestic ironing board. In mechanical ironing it is found that the pressure of the iron on this pad compacts the same so that a fresh pad is 80 always considerably thicker than one which has been used for any time. Since the shirt bosom rests on this paid it is essential that the base of the collar band holder shall lie in the same plane as the surface of the pad. 85

A fourth important object of the invention is to provide an improved arrangement 90 of collar band holder so mounted as to be adjustable for different thicknesses of pad and also to be adjustable for the proper positioning of the collar band with the recess of the iron.

It is usual in shirt ironing machines to provide means for holding the bosom stretches, such means commonly consisting 95 of traction devices for drawing the tail portion of the front of the shirt downward on the platen away from the collar band holder.

A fifth important object of the invention is to provide an improved form of collar 100 band holder which is so designed and constructed as to securely clamp the front portion of the collar band in proper position for ironing and with sufficient force to prevent slipping when the shirt is stretched by 105 drawing upon the tail portions.

A sixth important object of the invention is to provide an improved construction of 110 collar band holder having operation locking features which act to prevent any uninten-

tional or accidental release of the collar band from the holder while at the same time being of such nature as to be readily released by the operator without undue application of force and thus tending to prevent fatigue in the operation.

With the above and other objects in view, the invention consists in general of certain novel details of construction and combinations of parts hereinafter fully described, 10 illustrated in the accompanying drawings, and specifically claimed.

In the accompanying drawings, like characters of reference indicate like parts in the 15 several views, and:

Figure 1 is a plan view of a collar band holder constructed in accordance with this invention.

Figure 2 is a rear elevation thereof.

20 Figure 3 is a side elevation of the collar band holder, the parts being shown in holding position in full lines and in releasing position in dash and dot lines.

Figure 4 is a section on the line 4—4 of 25 Figure 2.

Figure 5 is a detail end view of one of the locking dogs.

Figure 6 is a detail side view of said dog.

In the embodiment of the invention herein 30 illustrated there is provided a main or body portion having a base 10 the forward part of which is arcuate in outline while the rear part is straight, the rear edge being of less length than the greatest dimensions across 35 the arcuate part. Extending around the arcuate portion is an upstanding wall 11 the outer surface of which is inclined in such manner that it slopes inwardly from the bottom towards the top. At the rear central 40 portion of the body and extending upward from the base 10 is a rectangular boss 12 having a vertical opening 13 which reaches from top to bottom of the boss so that a stud bolt 14 may pass loosely therethrough. On 45 top of the boss 12 there is provided a rectangular washer or plate 15 through which the stud bolt 14 passes, a nut 16 being screwed on the upper end of said stud bolt. The lower end of this stud bolt 14 is screwed into the 50 top 17 of the platen and between the base 10 and the top 17 there is interposed a column consisting of a number of washers as indicated at 18, these washers being preferably of thin sheet metal so that the base 10 55 may be held at any required distance above the platen top 17 and thus enable the usual pad or cover 19 to be placed on the platen. With this construction it becomes obvious 60 that the body of the device may be readily adjusted in a plane parallel to the platen top 17 by simply loosening the nut 16 and moving said body to the desired position. Also it is obvious that whenever the pad becomes 65 packed down by the action of the iron in the machine on which this collar band holder is

used the distance between the collar band holder and the platen top 17 may be quickly adjusted by merely removing the nut 16, lifting the entire device off and then removing as many of the washers 18 as are necessary to bring the collar band holder, when replaced in position, to the proper level with reference to the pad. In order to hold the pad 19 in position beneath the body of the device a series of acutely pointed pins or spikes 70 75 20 are provided which extend downward from the base 10 and thus project into and grip the material of the pad 19.

Extending through the boss 12 from front to rear thereof are guide pins 21, these pins 80 being disposed one on each side of the opening 13. On the rear ends of these guide pins is mounted a cross bar 22 which thus has motion toward and from the boss 12. At each end of the bar is formed a journal 23 85 provided with an annular groove 24 about midway of its length. Fitted on the journals 23 are cylindrical bosses 25 projecting from clamping band end members each of which is provided with an inclined body 26 90 having a channel 27 in its outer face, the body 26 extending downward so that its lower edge is practically in the plane of the bottom of the base 10. Surrounding the arcuate portion of the main body of 95 the device is a clamping band 28 which is preferably formed of spring metal such as brass or the like and which has its ends somewhat reduced in height so that it may fit within the respective channels 27 and be there held by suitable rivets or other securing device such as shown at 29. It is to be particularly noted that the channel 27 is so arranged that it is tangent to the arc of curvature of the outer surface 100 of wall 11. By this arrangement the clamping bar 28 is caused to fit smoothly around the wall 11 without an abrupt bend at any place. Projecting forwardly from the front of the wall 11 is a lip 30 having its under 110 surface substantially perpendicular with the outer surface of the wall 11 so that a lip 31 formed by bending the middle upper portion of the band 28 downward may engage beneath this lip 30. When the lip 31 is engaged beneath the lip 30 it will be obvious that the band 28 cannot be swung upward at its front end although, after the bar 22 be moved forwardly as indicated in the dot and dash lined position of the parts in Figure 3 the lip 31 will be freed from the lip 30 and the clamping band 28 may then be 115 swung upward on the journals or trunnions 23 as clearly shown in the dash and dot line portion in said Figure 3.

In order to provide for moving the band 22 toward and away from the boss 12 there is provided a yoke member having a body portion 32 and legs 33, which legs straddle the boss 12 and are pivoted to the side there- 120 125 130

of by means of counter-sunk screws 34, the axes of the screws being of course alined so that the yoke may be swung forwardly and rearwardly of the device. The lower ends of the legs 33 are provided with rearwardly extending portions 35 in which are fitted screw pins 36. These pins pass through slots 37 which are formed in the body portions 38 of drag links or members each of which has a flat lower end 39 resting on the top of the base 10. Moreover each of these members 38 is provided with a rearwardly extending stem 40 which passes loosely through the bar 22 and receives on its outer end a nut 41 and lock nut 42. On the stem 40 is also fitted a collar 43 and surrounding each stem between its collar and the bar 22 is a compression spring 44. It is to be observed that the lower end of the slot 37 has a shallow notch 45 at its rear side. It will be noted that when the parts are in the full line position shown in Figure 3 the pin 36 is received in the notch so that the handle 46 of the yoke is restrained from flying forward. At the same time the spring 44 presses the bar 22 backward so as to draw the band 28 tightly into position on the body of the device. It is obvious that by means of the nuts 41 and 42 the tension of the springs 30 may be adjusted and also the band 28 may be adjusted to give the required degree of pressure between said band and the inclined arcuate face of the body of the device.

In operation the collar band holder is first adjusted on the platen. This is accomplished by adjusting the height of the column of washers to the thickness of the pad and placing the collar band holder over the bolt with the washer or plate 15 in position on the upper end of said bolt. The movable iron used with ironing machines of this character is then brought into position on the pad just as though it was to be used for ironing. The collar band holder is adjusted laterally into proper position relative to this movable iron and the other screwed down on the stud bolt. This adjustment can very rapidly be accomplished and when in position the device is ready for holding the collar band during ironing.

The garments having been properly placed for the ironing operation the operator pulls the handle 46 forward in the direction indicated by the dash and dot line in Figure 3. This causes the yoke to rotate on the pins 34 and carries the pins 36 upward and forward. These pins in their movement pass upward in the slots 37 and move the members 38 forward so that the flexible band 28 is disengaged from beneath the lip 30. When the lever or handle 46 has been thus moved and the band is advanced far enough to clear the lip the operator, by means of the lip 31 on the band lifts the front of this band upward and rotates the same backward out of

the way preparatory to placing the neck band into position. The shirt to be ironed is then grasped in such manner as to fit over the rear end of the platen with the front of the neckband brought forward until the front ends of the band engage around the neckband holder being positioned by the operator on the inclined yoke surface of the holder body. The flexible band 28 is now rotated forward and downward so that it encloses the shirt neckband at its forward portion and is ready to grasp the same. It is to be noted that the neckband of the shirt is placed into position with the ends adjacent but not over-lapping. The handle 46 is now pushed backward and this causes the band 28 to be drawn against the neckband of the shirt thus clamping it securely against the body of the holder. As the lever is pushed back the pins 36 drop into the notches 45 and the lever is thus automatically locked into position. Under these conditions the springs 44 are somewhat compressed and thus serve to securely grip the collar band of the shirt.

It is to be noted that the entire operation is accomplished from the front end of the machine by the operator with one hand since the same hand which accomplishes the forward and return movement of the lever or handle 46 is also used to pick up and drop the band 28.

It is to be noted that under the conditions above explained the shirt collar band is never stretched nor does it require buttoning at the front. Consequently there is no danger of tearing out the buttonhole. Furthermore, with a collar band holder of this description the necessity of a yoke clamp for the shirt is entirely eliminated since the back of the shirt band is bent down and under the rear of the clamp by the adjustment of the shirt on the platen.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. A collar band holder for ironing machines including cooperating clamping members one of which includes a flexible band and is mounted to swing into and out of cooperative relation with the other and to move rectilinearly into and out of collar band clamping positions, and means associated with the said members and arranged to latch the swinging member releasably in coopera-

tive relation with the other member, said means including spring pressed elements arranged to hold the movable member yieldably pressed toward the other clamping member.

2. A collar band holder for ironing machines including cooperating clamping members one of which includes a flexible band and is mounted to swing into and out of cooperative relation with the other, and a lip on the other member engageable over the swinging member when the latter is in clamping position to prevent swinging thereof, said swinging member being movable rectilinearly between positions of engagement with and freedom from said lip, and latch means associated with said members and arranged to hold the swinging member from accidental movement from beneath said lip, said latch means having yieldable connection with the swinging member arranged to permit slight rectilinear movement thereof.

3. A collar band holder for ironing machines including a pair of cooperating clamping members, a pivotal support for one of the members having slidable connection with the other whereby the first member may swing into and out of cooperative position with relation to the other and move rectilinearly into and out of clamping position, means associated with said members and arranged to prevent swinging movement of the first member when in clamping position, and latch means associated with the support and the second member and arranged to hold the first member yieldably in clamping position.

4. A collar band holder for ironing machines including a pair of cooperating clamping members, a pivotal support for one of the members having slidable connection with the other whereby the first member may swing into and out of cooperative position with relation to the other and move rectilinearly into and out of clamping position, means associated with said members and arranged to prevent swinging movement of the first member when in clamping position, and latch means associated with the support and the second member and arranged to hold the first member releasably in clamping position, said latch means including a yieldable spring connection with the support whereby to permit slight rectilinear yielding of the swinging member.

5. A collar band holder for ironing machines including a pair of cooperating clamping members, a pivotal support for one of the members having slidable connection with the other whereby the first member may swing into and out of cooperative position with relation to the other and move rectilinearly into and out of clamping position, a lip on the second member arranged

to engage over the latter when it is in clamping position whereby to hold the same against swinging movement, and latch means associated with the support and the second member and arranged to hold the first member yieldably in clamping position.

6. A collar band holder for ironing machines including a pair of cooperating clamping members, a pivotal support for one of the members having slidable connection with the other whereby the first member may swing into and out of cooperative position with relation to the other and move rectilinearly into and out of clamping position, a lip on the second member arranged to engage over the latter when it is in clamping position whereby to hold the same against swinging movement, and latch means associated with the support and the second member and arranged to hold the first member releasably in clamping position, said latch means including a yieldable spring connection pressing the two members together whereby to permit slight rectilinear yielding of the swinging member.

7. A collar band holder for ironing machines including a pair of cooperating members, one of said members constituting a base and the other a clamp, a bar extending transversely across the rear of the base, means to support the bar arranged to permit movement of said bar toward and from said base, journal ends on said bar whereon said clamp is pivoted, and cooperating means on the base and clamp for holding the clamp from pivotal movement when the clamp is moved to operative position for clamping a collar band.

8. A collar band holder for ironing machines including a pair of cooperating members, one of said members constituting a base and the other a clamp, a bar extending transversely across the rear of the base, means to support the bar arranged to permit movement of said bar toward and from said base, journal ends on said bar whereon said clamp is pivoted, cooperating means on the base and clamp for holding the clamp from pivotal movement when the clamp is moved to operative position for clamping a collar band, and latch means for yieldably holding the clamp in clamping relation to the base.

9. A collar band holder for ironing machines including a pair of cooperating members, one of said members constituting a base and the other a clamp, a bar extending transversely across the rear of the base, means to support the bar arranged to permit movement of said bar toward and from the said base, journal ends on said bar whereon said clamp is pivoted, and a pair of cooperating lips on the front upper portion of the base and clamp, the lip on the clamp being arranged to engage beneath the lip on the base by movement of the bar away from

- said base when the clamp is pivotally swung into position for clamping whereby to prevent said clamp swinging out of such position while holding a collar band.
- 5 10. A collar band holder for ironing machines including a pair of cooperating members, one of said members constituting a base and the other a clamp, a bar extending transversely across the rear of the base, means to support the bar arranged to permit movement of said bar toward and from said base, journaled ends on said bar whereon said clamp is pivoted, a pair of cooperating lips on the front upper portion of the base and clamp, the lip on the clamp being arranged to engage beneath the lip on the base by movement of the bar away from said base when the clamp is pivotally swung into position for clamping whereby to prevent said clamp swinging out of such position while holding a collar band, and latch means for yieldably holding the clamp in clamping relation to the base.
- 15 11. A collar band holder for ironing machines including a pair of cooperating members, one of said members constituting a base and the other a clamp, a bar extending transversely across the rear of the base, means to support the bar arrangement to permit movement of said bar toward and from said base, journaled ends on said bar whereon said clamp is pivoted, a pair of cooperating lips on the front upper portion of the base and clamp, the lip on the clamp being arranged to engage beneath the lip on the base by movement of the bar away from said base when the clamp is pivotally swung into position for clamping whereby to prevent said clamp swinging out of such position while holding a collar band, and a combined bar moving and latching means mounted on said base and having connection with bar and arranged to hold said bar releasably forced away from the base.
- 20 12. A collar band holder for ironing machines including a pair of cooperating members, one of said members constituting a base and the other a clamp, a bar extending transversely across the rear of the base, means to support the bar arranged to permit movement of said bar toward and from said base, journaled ends on said bar whereon said clamp is pivoted, a pair of cooperating lips on the front upper portion of the base and clamp, the lip on the clamp being arranged to engage beneath the lip on the base by movement of the bar away from said base when the clamp is pivotally swung into position for clamping whereby to prevent said clamp swinging out of such position while holding a collar band, and a combined bar moving and latching means mounted on said base and having connection with bar and arranged to hold said bar releasably forced away from the base and including a spring
- 25 connection arranged to accommodate the clamp to various clamping positions.
13. A collar band holder for ironing machines including a pair of cooperating members one of which constitutes a base and the other a clamp, said base having its forward surface of substantial segmento-frustoconical shape, said clamp comprising a resilient band having a shape to fit the forward surface of the base, bearing members on the rear ends of said clamp, a bar extending transversely across the rear of the base and provided with journal ends fitting in said bearings to provide pivotal mounting for the clamp, and means to support the bar arranged to permit movement of the bar toward and from the base whereby to move the clamp away from and towards the clamping surface of the base.
- 30 14. A collar band holder for ironing machines including a pair of cooperating members one of which constitutes a base and the other a clamp, said base having its forward surface of substantial segmento-frustoconical shape, said clamp comprising a resilient band having a shape to fit the forward surface of the base, bearing members on the rear ends of said clamp, a bar extending transversely across the rear of the base and provided with journal ends fitting in said bearings to provide pivotal mounting for the clamp, means to support the bar arranged to permit movement of the bar toward and from the base whereby to move the clamp away from and towards the clamping surface of the base, a lever pivoted on the base and provided with a handle projecting upward from the base, and an operative connection between said lever and bar arranged to move the bar as the lever is moved.
- 35 15. A collar band holder for ironing machines including a pair of cooperating members one of which constitutes a base and the other a clamp, said base having its forward surface of substantial segmento-frustoconical shape, said clamp comprising a resilient band having a shape to fit the forward surface of the base, bearing members on the rear ends of said clamp, a bar extending transversely across the rear of the base and provided with journal ends fitting in said bearings to provide pivotal mounting for the clamp, means to support the bar arranged to permit movement of the bar toward and from the base whereby to move the clamp away from and towards the clamping surface of the base, a lever pivoted on the base and provided with a handle projecting upward from the base, an operative connection between said lever and bar arranged to move the bar as the lever is moved and including springs arranged to effect yieldable rearward pressure on said lever.
- 40 16. A collar band holder for ironing ma-

chines including a pair of cooperating members one of which constitutes a base and the other a clamp, said base having its forward surface of substantial segmento-frusto-conical shape, said clamp comprising a resilient band having a shape to fit the forward surface of the base, bearing members on the rear ends of said clamp, a bar extending transversely across the rear of the base and 5 provided with journal ends fitting in said bearings to provide pivotal mounting for the clamp, means to support the bar arranged to permit movement of the bar toward and from the base whereby to move the 10 clamp away from and towards the clamping surface of the base, a lever pivoted on the base and provided with a handle projecting upward from the base, an operative connection between said lever and bar arranged 15 to move the bar as the lever is moved and including springs arranged to effect yieldable rearward pressure on said lever, and a lip on the upper front edge of the base engageable over the clamp upon rearward 20 movement of the bar.

17. A collar band holder for ironing machines including a pair of cooperating members one of which constitutes a base and the other a clamp, said base having its forward surface of substantial segmento-frusto-conical shape, said clamp comprising a resilient band having a shape to fit the forward surface of the base, bearing members on the rear ends of said clamp, a bar 25 extending transversely across the rear of the base and provided with journal ends fitting in said bearings to provide pivotal mounting for the clamp, means to support the bar arranged to permit movement of the bar toward and from the base whereby to move the clamp away from and toward 30 the clamping surface of the base, a lever pivoted on the base and provided with a handle projecting upward from the base, an operative connection between said lever and bar arranged to move the bar as the lever 35 is moved, a lever pivoted on the base to swing forwardly and rearwardly and provided with an upwardly projecting handle, an operating member having a stem extending rearwardly through said bar and provided with a nut on its rearwardly projecting end, said member having a head provided with a vertical slot provided with a 40 recess in its rear wall, a pin carried by said lever and projecting into said slot whereby to effect rectilinear movement of the operating member, said pin being receivable in said recess to effect 45 releasable latching, a collar on said operating member, and a spring interposed between said collar and bar whereby to permit yieldable movement of the bar relative to the operating lever, and a lip on the upper 50 front edge of the base engageable over the clamp upon rearward movement of the bar. 105

In testimony whereof I affix my signature.

CECIL H. BOYULS.
